UNITED STATES PATENT OFFICE

CHARLES T. HATCH, OF ALBION, MICHIGAN, ASSIGNOR TO UNION STEEL PRODUCTS COMPANY, OF ALBION, MICHIGAN

RACK FOR REFRIGERATORS, OVENS, AND LIKE COMPARTMENTS

Application filed October 13, 1930. Serial No. 488,233.

The main object of this invention is to provide a rack for refrigerator, oven and like compartments which permits the removal of the shelves for cleaning or for use as trays as occasion may require, and at the same time a rack which may be freely manipulated into and out of the compartment.

A further object is to provide a structure which is well adapted for mounting in compartments having enameled or porcelain walls without injury thereto.

Objects pertaining to details and economies of my invention will definitely appear from the description to follow. The invention is defined in the claims.

A structure embodying the features of my invention is clearly illustrated in the accompanying drawing, in which:

Fig. 1 is a fragmentary perspective view of a refrigerator compartment with my improved rack structure mounted therein, the door being omitted and the refrigerator parts being shown conventionally for convenience in illustration.

Fig. 2 is a detail view partially in horizontal section.

Fig. 3 is a fragmentary view partially in section on line 3—3 of Fig. 2 with the shelf illustrated in one position by dotted lines and in another position illustrating the manner of inserting and removing it by full lines.

In the embodiment illustrated 1 represents a refrigerator and 2 one of the compartments thereof. My improved rack comprises strap or bar-like support members 3 having key-hole slots 4 adjacent the ends thereof adapted to be engaged with studs 5 projecting from the side walls of the compartment. Each of these supports carries shelf rails 6 formed of rods or heavy wires and have laterally turned ends 7 which are fixedly secured to the support members 3.

It will be understood that these support members are arranged on opposite side walls so that the rails are supported in opposite pairs.

The rails are provided with downwardly projecting loop-like offsets 8 adjacent their front ends. These offsets provide downwardly projecting front stops. The rails are

also provided with upwardly projecting loop-like offsets 9 adjacent their rear ends providing upwardly projecting stops.

The racks comprise border frames formed of heavy wire or light rods, and the border frames comprise side members 9, rear members 10 and front members 11 preferably formed integrally as shown in the drawing. The side members 9 have inwardly offset loops 11, the bight portions 12 of which are inclined to the horizontal so that the arms 13 of these loops ride upon the rails constituting supporting members, while the arms 15 of the loops project under the rails constituting supporting members when the rack is drawn outwardly to the position shown in dotted lines in Fig. 3; that is, they support the rack against tilting movement and the rack rides on the front laterally offset portions 7 of the rails, see Fig. 2.

These parts 15 also coact with the stops 8 limiting the forward movement of the rack while the parts 13 coact with the stops 9, limiting the rearward movement of the rack.

The ends of the rear frame member 10 are downwardly offset at 16 and are joined to the arms 7 of the offsets 12 by the loops 17, see Fig. 2. The offsets 16 engage the inner sides of the rails preventing lateral swinging of the rack as it is drawn out of or inserted into the oven or other compartment, thereby keeping the side members of the rail out of contact with the walls of the compartment and consequently preventing marring or injury to the walls.

To insert the rack the arm 13 of the rail offset is placed upon the rails in front of the offsets 8 thereof, the rack moved rearwardly and at the same time swung upwardly to bring the arms 15 to the rear of the stop 8. The rack is then moved in and out as desired and is effectively supported in any of its adjusted positions. The stop 9 is positioned so that the rack cannot be pushed into engagement with the rear wall of the compartment and thereby mar or injure it.

My improved rack structure is especially desirable for use in refrigerators, ovens and the like, having surfaces finished with enamel or porcelain, or other linings which it is de-

sired shall not be marred or which might be injured by a blow such as bringing a rack into contact therewith with considerable force.

5. Racks embodying my improvements may be freely manipulated without liability of such an occurrence.

I have not attempted to illustrate and describe my improvements in various modifications and adaptations thereof which I contemplate as it is believed that this disclosure will enable those skilled in the art to embody or adapt the same as may be desired.

Having thus described my invention what 15 I claim as new and desire to secure by Letters Patent is:

1. In a rack for refrigerator, oven and like compartments, the combination of support members adapted for detachably mounting 20 on the walls of a compartment, rod-like shelf rails having laterally turned ends secured to said support members, said rails having downwardly projecting loop-like offsets adjacent their front ends providing downward- 25 ly projecting front stops and upwardly projecting loop-like offsets adjacent their rear ends providing upwardly projecting rear stops, and a shelf comprising a border frame, the side members of which are slidably sup- 30 ported on the laterally turned front ends of said rails and have inwardly projecting loop-like offsets at their rear ends, the bight portions of the offsets being inclined rearwardly and downwardly so that the front 35 arms of the offsets ride upon the rails to support the shelf and coact with the rear stops and their rear arms project under the rails supporting the shelf against downward tilting when the shelf is extended and coact with the front stops, the ends of the rear border member of the shelf being downwardly offset and joined to the rear arms of the offsets of 40 said border frame side members.

2. In a rack for refrigerator, oven or like 45 compartments, the combination of support members adapted for detachably mounting on the walls of a compartment, rod-like shelf rails having laterally turned ends secured to said support members, said rails having 50 downwardly projecting loop-like offsets adjacent their front ends providing downwardly projecting front stops and upwardly projecting loop-like offsets adjacent their rear ends providing upwardly projecting rear 55 stops, and a shelf comprising side members slidably supported on the laterally turned front ends of said rails, said members having inwardly projecting loop-like offsets at 60 their rear ends, the bight portions of the offsets being inclined rearwardly and downwardly so that the front arms of the offsets ride upon the rails to support the shelf and coact with the rear stops and their rear arms 65 project under the rails supporting the shelf

against downward tilting when the shelf is extended and coact with the front stops.

3. In a rack for refrigerator, oven and like compartments, the combination of rod-like shelf rails having laterally turned ends, said rails having downwardly projecting loop-like offsets adjacent their front ends providing downwardly projecting front stops and upwardly projecting loop-like offsets adjacent their rear ends providing upwardly projecting rear stops, and a shelf comprising a border frame, the side members of which are slidably supported on the laterally turned front ends of said rails and have inwardly projecting loop-like offsets at their rear ends, the bight portions of the offsets being inclined rearwardly and downwardly so that the front arms of the offsets ride upon the rails to support the shelf and coact with the rear stops and their rear arms project under the rails supporting the shelf against downward tilting when the shelf is extended and coact with the front stops, the ends of the rear border member of the shelf being downwardly offset and joined to the rear arms of the offsets of 70 said border frame side members.

4. In a rack for refrigerator, oven or like compartments, the combination of rod-like shelf rails having laterally turned ends, said rails having downwardly projecting loop-like offsets adjacent their front ends providing downwardly projecting front stops and upwardly projecting loop-like offsets adjacent their rear ends providing upwardly projecting rear stops, and a shelf comprising side 75 members slidably supported on the laterally turned front ends of said rails, said members having inwardly projecting loop-like offsets at their rear ends, the bight portions of the offsets being inclined rearwardly and downwardly so that the front arms of the offsets ride upon the rails to support the shelf and coact with the rear stops and their rear arms project under the rails supporting the shelf 80 against downward tilting when the shelf is extended and coact with the front stops.

5. In a rack for refrigerator, oven and like compartments, the combination of shelf rails having downwardly projecting loop-like offsets adjacent their front ends providing downwardly projecting stops, and a shelf comprising a border frame, the side members of which have inwardly projecting loop-like offsets disposed with their bights inclined so that one arm of each offset rides upon the rails to support the shelf and the other arm projects under the rails supporting the shelf against downward tilting movement when the shelf is extended and coacts with the stops limiting the movement of the shelf, the ends of the rear border member of the shelf being downwardly offset and joined to the rear arms of the offsets of said border frame side members.

6. In a rack for refrigerator, oven and like 1

compartments, the combination of shelf rails having downwardly projecting loop-like offsets adjacent their front ends providing downwardly projecting stops, and a shelf 5 comprising side members having longitudinal inwardly projecting loop-like offsets disposed with their bights inclined so that one arm of each offset rides upon the rails to support the shelf and the other arm projects 10 under the rails supporting the shelf against downward tilting movement when the shelf is extended and coacts with the stops limiting the movement of the shelf, said arms disposed under the rails being in the form of 5 loops, whereby to slidably engage said rails at longitudinally spaced points.

7. In a rack for refrigerator, oven and like compartments, the combination of shelf rails having projecting loop-like offsets providing 20 stops, and a shelf comprising side members having longitudinal inwardly projecting loop-like offsets disposed with their bights inclined so that one arm of each offset rides upon the rails to support the shelf and the 25 other arm projects under the rails supporting the shelf against downward tilting movement when the shelf is extended and one arm coacts with the stops limiting the movement of the shelf, said arms disposed under the 30 rails being in the form of loops, whereby to slidably engage said rails at longitudinally spaced points.

In witness whereof I have hereunto set my hand.

35 CHARLES T. HATCH.
